SUPPORTING HOOK

Filed Feb. 10, 1927

UNITED STATES PATENT OFFICE.

ANNA HARRIMAN MASTEN, OF SAN DIEGO, CALIFORNIA.

SUPPORTING HOOK.

Application filed February 10, 1927. Serial No. 167,293.

This invention relates to supporting hooks and the general object of the invention is to provide a readily detachable and portable hook or support for use on upright articles such as tent poles, beach umbrella handles, bed posts, and other like articles, the device being intended to be used wherever a portable and detachable hook is required.

A further object is to provide a device of this character which may be readily attached to any upright and when so attached will provide a plurality of outwardly projecting arms upon which articles may be supported or hung.

My invention is illustrated in the accompanying drawings wherein:—

Figure 1 is a perspective view of a portion of a post with my device applied thereto;

Fig. 2 is a top plan view of the supporting hook or hanger;

Fig. 3 is a front elevation thereof.

Referring to these drawings it will be seen that this article comprises a somewhat arcuate plate 10 having teeth 11 at its lower edge, these teeth being bent inward and downward. The upper edge of the plate 10 is formed to provide a plurality of radially directed arms or hooks 12 radiating outward from the plate, said plate being curved to approximately fit upon a post or like object. The plate is also formed to provide hooks 13 at opposite ends of the plate, these hooks being preferably, though not necessarily, formed as part of the plate. To one of these hooks there is attached a flexible connection 14 which may be a cord, strap, chain, or like member but which is preferably a relatively long cord.

This cord is adapted to be wrapped around

the post A upon which the article is supported and then engaged with one of the hooks. 40

In the use of this device, the plate 10 is applied against the face of the upright and the cord 14 wrapped around the post one or more times, and its free end engaged with one of the hooks or lugs. The teeth 11 will 45 engage with the upright or post and any weight upon the arms or hooks 11 will act to force these teeth more and more into the face of the post or upright and thus hold the device very securely and prevent it from slipping 50 downward. Obviously I do not wish to be limited to the use of a cord 14 as a means for engaging this part 10 with the post nor to the use of these hooks at both ends of the member 10, nor to these hooks as being formed 55 integral with the member 10.

I claim:—

As an article of manufacture, a supporting device or rack comprising a relatively broad, arcuate plate of sheet metal adapted to closely 60 embrace an upright, the plate at its lower edge being formed with inwardly and downwardly extended teeth, the upper margin of the plate having an integrally formed arm extending radially outward therefrom at an 65 angle to the plate and in a direction away the direction of the teeth, a flexible connection engaged at one end with one end of said plate and adapted to be wrapped around the upright, and means at the other end of 70 said plate with which the free end of the flexible connection may be engaged.

In testimony whereof I hereunto affix my signature.

ANNA HARRIMAN MASTEN.
